UNITED STATES PATENT OFFICE.

JERROLD F. WALTON, OF STURGIS, MICHIGAN.

CHAIR-BACK.

1,254,950.

Specification of Letters Patent. Patented Jan. 29, 1918.

Application filed April 26, 1915. Serial No. 23,835.

To all whom it may concern:

Be it known that I, JERROLD F. WALTON, a citizen of the United States, residing at Sturgis, in the county of St. Joseph and State of Michigan, have invented certain new and useful Improvements in Chair-Backs, of which the following is a specification.

This invention relates to improvements in chair backs, and particularly to improved means for securing the depending controlling arm for hinged chair backs.

This invention relates to the structure appearing in Letters Patent No. 1,137,246, issued April 27, 1915, and shows an improved and modified means for securing the arm in position on the back.

The object of my invention is to provide an improved attaching means for such an adjusting arm. Objects relating to details and economies of construction and operation will definitely appear from the detailed description to follow.

I accomplish the objects of my invention by the devices and means described in the following specification. The invention is clearly defined and pointed out in the claims.

A structure constituting a preferred embodiment of my invention is clearly illustrated in the accompanying drawing, forming a part of this specification, in which:

Figure I is a detail perspective view of the lower back portion of a chair back with the adjustable detachable arm in position.

Fig. II is an enlarged detail sectional view on a line corresponding to line 2-2 of Fig. I.

Fig. III is a detail view of a portion of the arm showing the manner of striking up the engaging lug.

Fig. IV is a detail view of the blank for the bottom clip member showing the formation of the slot for the bayonet joint.

Fig. V is an enlarged detail view of a modification of the structure.

In the drawing similar numerals of reference refer to similar parts throughout the several views, and the sectional views are taken looking in the direction of the little arrows at the ends of the section lines.

Considering the numbered parts of the drawing, the chair back is made up of side

bars 1, 1 and bottom cross bar 2 and cross bars 3, 3 above the same. Secured to the cross bars is a vertical arm 4 having a straight round shank. Secured to the bottom cross bar 2 is a clip 5 by means of screws 6. This clip has a bayonet slot 7 on its under side. I strike up a lug, or otherwise form a lug or projection 11 on the side of the arm 4 to coöperate with the said bayonet slot when the arm 4 is inserted. I provide sheet metal clips 12, 12 on the backs of the cross bars 3, 3 which are secured by suitable screws 13. It will be seen that the arm 4 is effectively retained in place by this bayonet joint and the clip pieces retain the same on the cross bars so that the same is very effectively supported.

This structure affords a cheap and effective means for securing the bar in place, although it is not so well finished or so effective as the structure of my patent referred to.

In Fig. V I show a modification of the structure. A simple clip 5 is provided at the bottom without the bayonet slot 7. A clip for the upper end of the bar 14 is secured to an upper cross bar 3 and is provided with an off-set stop 15 for the upper end of the arm 4. The lug 11 is of such form that it can be passed up in the angle between the clip piece 5 and the bottom cross bar 2 and then turned toward the back part of the chair to engage above the top of clip 5, as clearly appears in Fig. V.

I desire to state that this structure can be considerably modified without departing from my invention, as pointed out in the appended claims.

Having thus described my invention, what I claim as new and desire to secure by Letters Patent, is:

1. The combination with an adjustable chair back of a detachable arm with a round straight shank part, clip members secured to the back sides of the cross bars of said back, embracing the said shank, the clip member on the bottom bar being provided with a bayonet joint slot, a projection on the said arm to engage the said bayonet joint slot to support the arm in position, as specified.

2. In a chair the combination of a hinged back; a detachable arm in said back; sheet metal clips embracing said arm and retain-

ing it to the said back; a lug on said arm for engaging one of said clips; stop means for limiting the upward movement of said arm, as specified.

5 3. In a chair, the combination of a hinged back comprising side and cross bars, a detachable arm in said back with a round straight shank, clips mounted on said cross bars and embracing said arm retaining the 10 same in position, and means on said arm co-

acting with one of said clips to support the arm longitudinally.

In witness whereof, I have hereunto set my hand and seal in the presence of two witnesses.

JERROLD F. WALTON. [L. S.]
